Des. 188,913
Patented Sept. 27, 1960

188,913

LIGHT DIFFUSIVE GRILLE

Morrison John Brounn, Flushing, N.Y., assignor to Otis
Elevator Company, New York, N.Y., a corporation
of New Jersey

Filed Sept. 24, 1957, Ser. No. 47,840

Term of patent 14 years

(Cl. D48—16)

FIG. 1

FIG. 2

FIG. 3

Figure 1 is a plan view of my light diffusive grille showing my new design;

Figure 2 is a cross-sectional view along line 2—2 of Figure 1, the dotted lines shown being for illustrative purposes only; and

Figure 3 is a fragmentary bottom perspective view to a larger scale.

I claim:

The ornamental design for a light diffusive grille, substantially as shown and described.
